CLAIM

The ornamental design for an aerial vehicle as shown and described.

DESCRIPTION

FIG. 1 is a top-down perspective view of an aerial vehicle of the present invention;

FIG. 2 is a front view thereof;

FIG. 3 is a side view thereof;

FIG. 4 is a top view thereof; and,

FIG. 5 is a perspective view thereof.

The broken lines depict portions of the aerial vehicle that form no part of the claimed design.
